(57) **CLAIM**

The ornamental design for a tire repair system as shown and described.

DESCRIPTION

FIG. 1 is a perspective view of a tire repair system;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear side elevation view thereof; and,

FIG. 7 is a front side elevation view thereof.

The broken lines in the drawings illustrate portions of the tire repair system that form no part of the claimed design.

1 Claim, 6 Drawing Sheets
